UNITED STATES PATENT OFFICE

LOUIS A. SCHMIDT, OF BROOKLYN, NEW YORK, ASSIGNOR TO R. HOE & CO., INC., OF NEW YORK, N. Y., A CORPORATION OF NEW YORK

CUTTING AND FOLDING MECHANISM FOR USE WITH WEB PRINTING MACHINES

Application filed January 22, 1929. Serial No. 334,338.

The present invention relates to folders for web printing machines. These folders are commonly made with two formers arranged side by side, over each of which, one-half width webs are passed to receive a first fold and are thence led to cutting and folding cylinders which cut the web or webs into sheets. These sheets then receive a second fold as they leave the folding cylinder and are passed on to a delivery mechanism.

When the entire product of the press is to be combined to form a single complete product the webs that have passed over one former are sometimes associated with the webs that have passed over the other former and they are both cut and folded together. By this means the combined product is cut at one time and the number of pages in the product is limited by the capacity of the cutting cylinder.

With the invention disclosed herein, the product passing over each former is cut separately and the two products are then associated to form a complete product, which may be of twice the number of pages that would be possible if they were all cut together.

The especial object of the invention is to provide a cutting and folding mechanism adapted to cut, fold and deliver products that are too heavy to be satisfactorily cut by mechanism heretofore used.

Another object of the invention is to provide cutting and folding mechanism adapted to either separately cut, fold and deliver the product from webs coming from two formers, or to separately cut them and thereafter associate, fold and pass the products on to a delivery as a combined product.

It is also an object of the invention to provide a cutting and folding mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described

and claimed, it being understood that various changes in the precise embodiment of the invention herein disclosed may be made within the scope of what is claimed without departing from the spirit of the invention.

The accompanying drawing shows a portion of a folder that is similar to those commonly used with web printing machines but an additional cutting cylinder and a transfer cylinder are shown as the preferred embodiment of the invention.

Portions of the two formers over which the webs are led to receive the first fold, are shown at 11 and 12, the usual bending rollers being shown and designated 13, 13', 14, 14', 15 and the nipping rollers 15, 15', 16 and 16'.

Guide rollers are indicated at 17, 18 and 19, the cutting cylinders used for straight runs at 20 and 21, the folding cylinders at 22 and 23, the folding-off rollers at 24, 24', 25 and 25', and the delivery fan wheels at 26 and 27.

The cutting cylinder used when the webs from both formers are to be associated is indicated at 28 and the transfer cylinder at 29.

The cutting cylinders each have cutting knives and they are indicated at 31, 32 and 33. They also have collecting pin mechanisms indicated at 34, 35 and 36.

Similar collecting pin mechanisms 37, 37', 38, 38', 39 and 39' are carried by the folding cylinders 22 and 23, and by the transfer cylinder 29, and folding blades 41, 41', 42 and 42' are carried by the folding cylinders.

It will be understood that means not shown are provided for driving the nipping rollers, the cutting, collecting and transfer cylinders, the folding-off rolls, and the fan wheels; also that the collecting pin mechanism and the folding blades are operated in proper timed relation to the cylinders by well known means.

In operation, the web or webs passing over the former 11 are drawn therefrom by the nipping rollers 15 and 15', they then pass around the guide roller 17, and between the cutting cylinder 20 and the folding cylinder 22, where they are cut by the cutting blade 31.

On a non-collect run the product cut from the web is carried around the cylinder by the pins 37 and given its final fold when the blade 41 engages the folding-off rolls 24 and 24'.

It is then passed to the fan wheel 26 of the delivery.

On a collect run the web is taken by the pins 34 on the cutting cylinder 20, and carried around it. The leading end of the cut section is then associated with the leading end of the web and impaled on the pins 37. The collected product is then folded off as before described.

10 Similarly the webs passing over the former 12 are drawn by nipping rollers 16 and 16', pass between the cutting cylinder 21 and the folding cylinder 23, are cut, then folded by the blade 42 between the rollers 25 and 25', and pass to the delivery, forming a single section product.

For a collected product alternate sections of the cut webs are carried around the cutting cylinder 21 and associated with the other sections as above described in connection with the webs from the former 11.

When it is desired to associate the product coming from the former 12 with that coming from the former 11, the web from the former 12 may be led as shown by the dotted line, around the nipping roller 16, the guide rollers 18 and 19, to and between the cutting cylinder 28 and the transfer cylinder 29, where it is cut by the blade 33, and the product then taken by the pins 39, which carry it to the cylinder 22, where it is impaled on the pins 37 or 37' and then folded off with the product coming from the former 11.

It will be understood that the pins 36 may be used to carry alternate cut sections around the cylinder 28 and associate them with the other sections cut from the web coming from the folder 12 in order to form a collected product and that the collected product can likewise be transferred to the folding cylinder 22.

It is thus possible to fold and pass to the delivery from the folding cylinder 22, a single section product, a two section collected product, a two section associated product, or a four section collected and associated product; or, the webs coming from each former may be operated on by the folding cylinder below it and be delivered either as a single section product or as a two section collected product.

What I claim is:

1. In a folder for a web printing machine, a pair of formers, a pair of delivery mechanisms, separate cutting and folding mechanisms located between each former and its delivery mechanism, and means for associating the products from both of the formers after they are cut, and folding them together and delivering them as a complete product.

2. In a folder for a web printing machine, a cutting cylinder, a folding cylinder and a delivery, adapted to receive webs, to cut them into sheets, to fold and to deliver said sheets, and a second cutting cylinder having a co-

acting transfer cylinder, adapted to receive other webs, to cut them into sheets, and to associate these last mentioned sheets with the first mentioned sheets before they are folded by the folded cylinder.

3. In a folder for a web printing machine having two formers and two delivery mechanisms, means including cutting, folding and transfer cylinders, whereby webs coming from one of the formers may either be cut, folded and passed on to its delivery mechanism, or the aforesaid webs may be cut, and then associated with the product which comes from the other former and which is separately cut.

4. In a folder for a web printing machine, a first cutting cylinder and a co-acting first folding cylinder, adapted to receive webs from a first former, cut them into sheets, fold and pass the cut sheets to a first delivery, a second cutting cylinder and a co-acting second folding cylinder, adapted to receive webs from a second former, cut them into sheets, fold and pass the cut sheets to a second delivery, and a third cutting cylinder and a co-acting transfer cylinder, adapted to receive webs from the second former, cut them into sheets and associate the cut sheets with those on the first folding cylinder, whereby a combined product may be passed to the first delivery.

5. In a folder for a web printing machine, two formers, two delivery mechanisms and means including cutting, folding and transfer cylinders, whereby webs coming from one of the formers may be cut, collected, folded and passed on to its delivery mechanism, or the aforesaid webs may be cut and collected and then associated with the product which comes from the other former and which is separately cut.

6. In a folder for a web printing machine, two formers, two delivery mechanisms, and means including cutting, folding and transfer cylinders, whereby a single section product or a two section associated product, or a two section collected product, or a four section collected and associated product may be cut, folded and delivered, each section of the product being cut separately.

7. In a folder for a web printing machine, two formers, two delivery mechanisms, and means including cutting, folding and transfer cylinders, whereby two single section products, or two two section collected products, or a two section associated product, or a four section collected and associated product may be cut, folded and delivered, each section of the product being cut separately.

In testimony whereof, I affix my signature.

LOUIS A. SCHMIDT.
